UNITED STATES PATENT OFFICE.

CHARLES J. AHRENFELDT, OF NEW YORK, N. Y.

DESIGN FOR A COVERED DISH.

SPECIFICATION forming part of Design No. 32,422, dated April 3, 1900.

Application filed January 8, 1900. Serial No. 788. Term of patent 7 years.

To all whom it may concern:

Be it known that I, CHARLES J. AHRENFELDT, a citizen of the United States, residing in the city of New York, county of New York, and State of New York, have invented and produced a new and original Design for a Covered Dish, of which the following is a specification, reference being had to the accompanying drawings, forming a part hereof, and like letters referring to like parts in each figure of the same.

In the said drawings, Figure 1 is a side view of a covered dish, showing my design. Fig. 2 is a top view of the same.

15 The body of the dish A is of elliptical outline and has a flared base B, while at the top it is provided with the vertical brim C, upon which rests the convex elliptical - shaped cover D.

20 The curved handle E of the cover is located at the top and center thereof. It is slightly fluted and is joined to the cover by leaf-shaped ornaments E', while at its upper part it has an

ornament E², which resembles a collar or band with leaves projecting therefrom in either direction. 25

The handles F are each composed of two upright fluted pieces F³, each of which describes a reverse curve. They are each joined to the body of the dish by a leaf-shaped ornament F' and provided with an ornament F², similar to the ornament E² of the cover-handle, while the upper ends of each pair of uprights are joined by a horizontal piece provided with an ornament F⁴, which is also similar to E². 30 35

What I claim is—

The design for a covered dish substantially as herein shown and described.

Signed at New York, N. Y., this 28th day 40 of December, 1899.

CHARLES J. AHRENFELDT.
